UNITED STATES PATENT OFFICE.

FREDERICK W. DERBYSHIRE, OF CHICAGO, ILLINOIS.

DOOR GUARD.

Application filed May 18, 1928. Serial No. 278,806.

This invention relates to door fastenings and to limited opening control means, and more especially to those attachments which are commonly known as door guards. Such devices are intended for adjustment to secure a partly open hinged door against opening wide, but permitting it to stand ajar or somewhat open, sufficient to provide ventilation, and they are so designed and arranged as to be normally operable only from the inside. Heretofore such devices have usually consisted substantially of a pair of members in the form of plates or "leaves" hinged together, one being adapted for fastening permanently to the door casing, as by screws or the like, either against the room side face of the casing where exposed to view, or in an appropriate notch in the door edge opposing part of the casing, and the complementary member being arranged to swing horizontally and project more or less into the room for detachable engagement with a fastening permanently secured to the inner side of the door. Such devices, although they have been extensively used for many years, have certain serious shortcomings and are accordingly objectionable for the reason that in the former arrangement, still sometimes used, they are unsightly, and in the latter arrangement, though neat in appearance, they may be readily made ineffective and operated abnormally by a person on the outside, through the removal of the fastening screws from the casing plate, which is exposed when the door is at all open.

The main objects of the present invention are to provide a door guard of improved form; to provide both for concealment of the fixed inner member of the check on the door edge of the casing and for protection against tampering therewith or removal thereof from the outside; to provide such a device adapted for ready door control engagement with the door when the latter is closed or nearly closed, and which is non-detachable therefrom when the door is swung inward somewhat; to provide a door guard of the general character described in which the swinging member is foldable back away from the door and against the inner wall of the casing or of the room when not in use; and to provide such a guard in which the swinging member is also swingable against the inner face of the door and into engagement therewith when the latter is closed for locking the same.

An illustrative embodiment of this invention is shown by the accompanying drawings in which:

Figure 1 is a horizontal section through a door and door casing just above the position of the door guard.

Fig. 2 is substantially an enlargement of the right-hand end of Fig. 1, with the free arm of the door guard swung back adjacent to the wall.

Fig. 3 is an enlarged vertical section on the line 3-3 of Fig. 1.

Fig. 4 is a side view of the guard engaging T-catch adapted to be fixed on the inner side of the door.

Fig. 5 is a side view of the door guard removed from the door and straightened out with all three parts in alignment.

Fig. 6 is a similar view of a modified form of door guard having only one hinge joint.

Fig. 7 is a view similar to Fig. 4 but showing a modified form of T-catch having a button thereon to lock the door closed tight.

In the construction shown in the drawings, the door guard 1 is adapted and arranged to engage the T-catch 2 fastened to the inner side of the door 3 at its free edge. As viewed in Fig. 1, said door occupies the doorway 4 when closed and is hinged at 5 to the left upright 6 of the door casing. The right-hand upright 7 of the door casing is recessed at 8 to accommodate the free edge of the door when closed and to provide a stop shoulder 9 for the door.

The door check 1 comprises a plurality of sections in the form of plates 10, 11 and 12 hinged together at 13 and 14 as shown by Fig. 5. The right-hand plate, as viewed in Fig. 5, is provided with holes 15 to receive the screws 16 for securing the guard permanently to the door jamb or casing member 7 as shown by Figs. 2 and 3. The middle or "link" section 11 is plain and, in ordinary use, at all times overlaps the face of the "anchorage" plate 10 and so protects the screws 16 against removal, the hinge 13 being disposed back adjacent to the corner of the guard seating recess hereinafter described. (See Figs. 1 and 2.) This plate 11 is somewhat longer than the plate 10 so as to accommodate free horizontal swing of the relatively long catch plate 12 for positions indicated in Figs. 1 and 2 respectively, and also for disposition against the inner side of the door when the latter is closed.

Said plate 12 is provided with a longitu-

dinal slideway or guide part. This is represented by the long central slot 17 which is substantially enlarged at its inner end 18 adjacent to hinge 14 to accommodate co-action 5 with the T-catch 2. This catch is provided with a horizontal offset arm 19, the extremity of which extends parallel with the door, and when the latter is closed overlaps somewhat the position of the door-guard as indicated in 10 Fig. 2. This arm part includes a narrow neck 20 to fit in the slot 17, and a head 21 admissible through plate 12 at the enlarged end 18 only of slot 17, as accommodated when the door is closed. The body part of catch 2 15 is provided with holes 22 for fastenings 23.

In order to accommodate the guard sections 10 and 11 snugly and unobtrusively in the door casing 7, the latter is provided with a recess 24 just back of and opening into the 20 main recess 8, which receives the free edge of the door when closed.

In the modified construction shown in Fig. 6, the guard 25 comprises an anchorage plate 26 to receive the fastening screws and a 25 slotted catch plate 27 to accommodate engagement with the T-catch 2 substantially as in the embodiment as described. In the device of Fig. 6, however, the main guard plate 27 extends back to the hinge 28 on the rear 30 edge of plate 26, and as plate 27 is rigid it cannot fold back either against the wall as in Fig. 2 or against the inner side of the door, but projects forward into the room somewhat at all times. The plate 26 has holes 29, and a 35 slot 30 is provided in plate 27. Although this form of guard is in effect similar to the device of Fig. 5 and offers similar protection against tampering from the outside, still the latter is somewhat preferable by reason of 40 the unobtrusive position of its catch plate 12 when not in use.

In applying the device of Fig. 5 to a door casing, the door should be swung wide open and then with the plate 10 in place in recess 45 24 and with the sections 11 and 12 disposed in alignment at about a right angle thereto the screws may be set in place. Then the sections 11 and 12 are swung to the position shown in Fig. 2, whereupon the door may be 50 closed. Then in case it is desired to use the guard, the section 12 is swung forward from its position shown in Fig. 2 to that shown in Fig. 1, whereby the head 21 of the T-catch passes through the aperture 18, and upon then 55 swinging the door inward, as in opening, the neck part 20 of the catch slides outward in the slot 17 until it assumes a position such as shown in Figs. 1 and 5. In this position, the door is open sufficiently to permit ventilation 60 and if desired the reception of articles such as mail, groceries, etc., but with sufficient limitation to prevent the admission of a person from the outside. Moreover, in this position the members 2 and 12 cannot be disengaged, 65 and this is true for any appreciable degree of

opening of the door with the guard in use. As will be apparent from Figs. 1 and 2, the fastening screws 16 for the anchorage plate 10 are protected from removal by the metal plate section 11 when the guard is set for service as in Fig. 1. 70

The modified form of T-catch 33, is mainly similar to catch 2. It has an arm 34 similar in shape to arm 19 except that it is narrow throughout to serve as a sort of extended neck, 75 and terminates in a T-head 35. This form permits the catch plate 12 to swing over against the body part 33 when the door is closed. Holes 36 accommodate screws or the like. A T-button 37 swings on its central 80 pivot 38 at the left end, as viewed in the drawings, to engage in the outer end of slot 17 when plate 12 is swung over against the door, whereby the check may serve as a lock to hold the door fully closed, as will be understood, 85 the button 37 being turned manually to the dotted position indicated.

Although certain specific embodiments of this invention have been selected to illustrate my improvements herein set forth, it is to be 90 understood that some of the details of the constructions shown may be altered or omitted without departing from the spirit of this invention as defined by the following claims:

I claim:

1. A door guard adapted for attachment to the door facing edge of a casing comprising an anchorage plate, a catch-plate and a link plate, the lattermost being hinged at its opposite edges to one end of the catch plate and to the rear end of said anchorage plate respectively, whereby the anchorage plate is protected against outside tampering when the door is open with the guard in use, said catch plate being formed adjacent to its inner end for connection and disconnection relative to the door, and having a longitudinal guideway to accommodate limited swinging of the door. 95

2. A door guard device of the character described comprising a catch adapted to be fixed on the free edge part of the door and a complementary jointed member adapted to be anchored to the door facing edge of the door casing in coactive relation to said catch, said jointed member comprising a perforated anchorage plate, a link hinged to the rear edge thereof and overlying the same and a catch plate hinged to the free edge of said link, said catch plate having a longitudinal slideway and said catch being formed to engage said slideway, the latter being formed at its hinge and part to permit connection and disconnection of said catch when the door is closed. 110

3. A door guard device of the character described comprising a catch adapted to be fixed on the free edge part of the door and a complementary jointed member adapted to be anchored to the door facing edge of the door casing in coactive relation to said catch, said 125

jointed member comprising a perforated anchorage plate, a link hinged to the rear edge thereof and overlying the same and a catch plate hinged to the free edge of said link, 5 said catch plate having a longitudinal slideway and said catch being formed to engage said slideway, the latter being formed at its hinge end part to permit connection and dis-

connection of said catch when the door is closed and said catch having means to releasably engage the free end part of said catch plate when the door is closed and the catch plate is swung substantially against the door. 10

Signed at Chicago this 16th day of May 1928.

FREDERICK W. DERBYSHIRE.
